UNITED STATES PATENT OFFICE.

CHARLES SONNEBORN, OF WEST PITTSBURG, PENNSYLVANIA.

SHARPENER FOR PENCIL LEADS.

Application filed May 15, 1922. Serial No. 560,894.

To all whom it may concern:

Be it known that I, CHARLES SONNEBORN, a citizen of the United States, and a resident of West Pittsburg, in the county of Lawrence and State of Pennsylvania, have invented a new and useful Improvement in Sharpeners for Pencil Leads, of which the following is a specification.

This invention relates to sharpeners, and particularly to a sharpening device intended for use in connection with pencil leads employed for drafting or other similar purposes, in which it is highly desirable to have the point of the lead accurately formed.

It is an object of the invention to provide a device for the above purpose which is simple in construction, efficient in operation, easy to manipulate, and economical to manufacture.

It is a special object to provide a sharpener which may be readily adjusted to produce points of varying length and thickness, as well as producing points which are either conical or of the so-called "chisel type."

It is a further object of the invention to provide a device in which new portions of the cutting faces of the cutting disks may be utilized from time to time as used portions thereof become dull, the new portions being brought into operation by a very simple adjustment of the guiding means for the lead. It is still a further object to provide a construction in which the lead is accurately centered and guided during the cutting operation whereby to secure symmetrically formed points.

These and other objects of the invention will more readily appear when taken in connection with the following description and the appended claims.

In the accompanying drawings, Fig. 1 is a plan view of the preferred embodiment of the invention; Fig. 2 a vertical transverse sectional view, with parts broken away, of the device illustrated in Fig. 1; Fig. 3, a fragmentary detail view in horizontal section of the adjusting means for varying the width of the pass between the cutting disks; Fig. 4, an end elevation, with parts broken away, illustrating the manner in which the lead is guided during the cutting operation; Fig. 5, an end elevation looking at the sharpener from the opposite end to that illustrated in Fig. 4; and Figs. 6 to 10 illustrate various forms of points produced by

different settings of the cutting disks and stop-guide for the holder of the lead.

The sharpener comprises the base 1 having formed thereon the upright standard 2, the upper enlarged head of which is provided with a guideway 3. Mounted for transverse sliding movement in the guideway 3 is a block 4 having at one end the elongated slot 5 to receive the body of a clamping bolt 6 threaded in the standard 2. The head 7 of the bolt 5 rests upon the upper surface of the block 4 so as to rigidly bind the same into locking engagement with the bottom of the guideway 3 after the desired setting has been made. The other end 70 of block 4 is provided with an interiorly threaded recess in which a cylindrical stop-guide 8 is mounted, said guide being exteriorly threaded for engagement with the threaded recess. The stop-guide is recessed 75 from end to end, as clearly shown in Fig. 2, and its upper extremity is flanged to provide a stop shoulder 9.

Pairs of spaced ears, indicated at 10, 10', and 11, 11', are formed upon the base plate 80 1 and disposed at opposite sides of the standard 2. Pivottally mounted in these ears by means of suitable trunnions are the arms 12 and 13, the upper ends of which are provided with the bearing heads 14 and 15 respectively. Journaled in the bearing 14 is a shaft 16, and similarly journaled in the bearing 15 is a shaft 17 to one end of which is attached the operating handle 18. Fixed to the opposite end of the shaft 17 is a spur gear 19 abutting the outer face of which is a cutting disk 20, both the gear 19 and disk 20 being fixed to the shaft by means of a nut 21. A similar gear 22 and a cutting disk 23 are likewise fixed to the adjacent end 90 of the shaft 14 by means of nut 24. The gear 19 is identical with gear 22, and the two disks are also identical with the exception that the abrading teeth formed on the periphery of the one when in assembled relation are inclined to those on the other. Although the cutting disks are preferably separate from the gears and are in the form of circular disks, they may be integral with the gears and of annular form, if desired. 100 The length of the teeth on these gears is sufficiently long to permit the arms 12 and 13 to be swung throughout an arc great enough to effect the desired variations in the width of the pass between the cutting disks, for a 110

purpose to be presently described, without causing disengagement of the gears.

Eyes 25 and 26 are disposed upon the respective bearings 14 and 15 with which the opposite ends of a coil spring 27 engage for urging the arms 12 and 13, together with their attached parts, towards each other. In order to limit the movement of these parts towards each other and to vary the width of the pass formed between the peripheries of the cutting disks, an adjusting screw bolt 28 and limiting pins 29 and 30 are mounted on the standard 2. The screw bolt 28 is provided with a reduced inner end 31 which is threaded into the body of the standard while the intermediate portion 32 thereof is beveled, as shown at 32, its outer extremity being provided with a knurled head 33. The bolt is mounted in a recessed boss 34 extending from the face of the standard, and the pins 29 and 30 are slidably mounted in a pair of similar auxiliary bosses 35 and 36 which extend horizontally from the main boss 34. The inner ends of the pins 29 and 30 abut the inclined or beveled portion 32 of the adjusting bolt, while their outer ends contact the pivoted arms 12 and 13. It is thus seen that rotation of the bolt 28 in one direction will cause the pins 29 and 30 to force the arms 12 and 13 farther apart, while rotation in the opposite direction will permit the spring 27 to move the same towards each other, and in this manner vary the width of the pass between the peripheries of the cutting disks to any desired setting.

Attached to the standard 2 by any suitable means such as by screws 37 and 38, and surrounding the gears 19, 22, and the cutting disks 20, 23, is a dust collecting receptacle 40, the lower portion 41 of which is depressed to form a collecting pocket, the open end of the receptacle being closed by a cover 42, the peripheral lip 43 of which slidably embraces the outer extremity of the said body and is held in position by frictional contact therewith.

In order to position the lead 44 during the cutting operation any suitable holder 50 may be used. The holder illustrated in the drawings is a specially constructed mechanical pencil with which the leads may be used and is indicated at 45. The detailed construction of the pencil forms the subject matter of a separate and independent application, Serial No. 540,535, filed March 2, 1922. The extremity of the holder is provided with a reduced cylindrical portion 46 which is adapted to snugly fit the bore of the guidestop 8, having free sliding movement therein, a shoulder 46 being provided thereon which is adapted to abut the shoulder 9 of the guide to limit the extent of movement of the holder and lead. Either 60 a pencil constructed in this manner, or a

specially formed holding device may be used for this purpose, it being understood that in either case the lead is inserted and held within an axial opening therein.

The operation of the device is as follows:

A lead to be sharpened is first positioned in the holding device the reduced portion 46 of which is then inserted in the bore of the stop-guide 8 with the tip of the lead resting in contact with the peripheries of the cutting disks, as illustrated in Fig. 4, the stop being adjusted vertically so as to leave a space between the shoulder 9 thereon and the shoulder 47 upon the holder. The cutter disks are then rotated by means of turning the handle 18, the lead being fed downwardly as it is cut away preferably under the weight of the parts or by slight pressure exerted by the operative. The holder and lead will continue to descend until the shoulder 47 contacts the shoulder 9, thus limiting further downward movement.

By varying the vertical setting of the guide-stop 8, and also the width of the pass between the cutting disks, a variety of points may be obtained. If the adjusting screw bolt 28 is set to permit the peripheries of the cutter disks to move into close proximity, and the stop 8 is moved to a position to permit the tip of the lead to descend to a point corresponding to the horizontal plane in which the centers of the cutting disks are located, a point provided with concave sides and a sharp chisel edge, such as illustrated in Fig. 6, will be formed. If the setting of the stop 8 is unchanged, and the width of the pass between the cutting disks be increased, a "chisel point" having a blunt edge, such as illustrated in Fig. 7, will be produced. A similarly shaped blunt edged "chisel point" may also be formed by adjusting the setting of the stop 8 while the cutting disks remain in their closely adjusted position, in which instance the lead is not permitted to descend entirely to the plane of the centers of the cutting disks. This method of forming such a point is illustrated in Fig. 8, it being noted that this point is similar to that illustrated in Fig. 7 with the exception that the concave portion is slightly shorter in proportion to the remaining parts than is the case in the preceding form. By setting the cutting disks slightly apart, as in Fig. 7, and adjusting the stop-guide 8 so as to permit the lead to descend below the plane of the centers of the cutting disks, a "chisel point" with an elongated point may be formed, such as illustrated in Fig. 9.

In each of the above instances, the holder and the lead have moved merely in a rectilinear direction downwardly during the cutting operation, that is, the holder and lead have not rotated, being held against rotation by the engagement of the sides of the lead

by the cutting faces of the disks, and hence the cutting of the lead has resulted in the formation of concave "chisel edge" points. By rotating the holder of the lead during the downward feeding of the same, all sides of the lead will be cut away, resulting in the formation of a conical point instead of one with a "chisel edge". Such a point formed with the parts set to produce a "chisel edge" point, such as illustrated in Fig. 6, is shown in Fig. 10. It is obvious that similarly formed conical points having tips of the desired fineness or bluntness may be secured by varying the settings of the width of the pass between the cutting disks and the descent of the lead in a manner analogous to that above described.

The width of the cutting disks is of a considerable extent, so that unused portions may be brought into operation after used portions thereof have become dull, thus prolonging the life of the device, or prolonging the time it may be used without renewing the cutting disks. In order to bring the unused portions of the disk into use, it is merely necessary to loosen the clamping bolt 6 sufficiently to slide the block 4 laterally so as to vary the position of the stop-guide 8 with respect to the cutting faces of the disks, after which the block 4 is again clamped into fixed position.

The guide-stop 8 is positioned directly above and in alignment with the pass between the cutting disks, and the reduced portion 46 of the holder 45 for the lead is made of such dimensions as to snugly fit the bore of the guide-stop. In this manner an accurately cut point which is symmetrically formed is assured. If at any time the parts should become worn so as to destroy the alignment, the same may be easily restored by removing the pins 29 and 30 and varying the length thereof by removing a greater or less quantity of metal from their ends, so as to adjust the pass between the disks to the point desired.

Although the cutting disks are preferably disks of metal having their peripheries provided with inclined cutting ridges of the file type, disks of any suitable material provided with peripheries formed with an abrading surface may be used without departing from the spirit of the invention. Likewise, although the receptacle for the dust resulting from the cutting of the lead is preferably made of a transparent material, the same may be made of any suitable material adapted for the purpose.

It is thus seen that the invention provides a simple, compact, economical and efficient sharpening device for the purpose intended, one which may be readily adjusted to secure a variety of forms of points, and one particularly adapted to produce points intended for drafting or other similar work

in which it is desirable to have points which are accurately and symmetrically formed.

I claim:

1. A sharpening device for pencil leads comprising a pair of rotary cutters, an adjustable stop-guide in alignment with the pass between the cutters, a holder for the lead freely mounted in the said guide and capable of independent rectilinear and rotary movement, and a shoulder on the holder adapted to contact a portion of the stop-guide to limit the travel thereof.

2. A sharpening device for pencil leads comprising a pair of rotary cutters adjustable bodily towards and from each other to vary the width of the pass therebetween, an adjustable stop-guide in alignment with the pass between the cutters, a holder for the lead freely mounted in the said guide and capable of independent rectilinear and rotary movement, and a shoulder on the holder adapted to contact the stop-guide to limit the travel thereof.

3. A sharpening device for pencil leads comprising a base, a pair of spaced arms pivoted thereto, a circular cutting disk rotatably mounted on each of said arms, means for constantly urging the disks towards each other, a guide in alignment with the pass between the disks, and means for rotating the said disks.

4. A sharpening device for pencil leads comprising a base, a pair of spaced arms pivoted thereto, a circular cutting disk rotatably mounted on each of the said arms, the disks being tangentially arranged to form a pass therebetween, means for constantly but yieldingly urging the disks towards each other, means for adjusting the width of said pass, a guide in alignment with the pass, and means for rotating the said disks.

5. A sharpening device for pencil leads comprising a base, a pair of spaced arms pivoted thereto, a shaft journaled in each of said arms, gears fixed to adjacent ends of said shafts meshing with each other, circular cutting disks fixed to said shafts and tangentially arranged to form a pass therebetween, a coil spring having its opposite ends attached to the arms for yieldingly urging said gears into mesh, means for adjusting the width of the pass between the disks, the length of the teeth of the gears being sufficient to permit such adjustment without causing disengagement thereof, a guide in alignment with the pass, and means for rotating said shafts.

6. A sharpening device for pencil leads comprising a base, a vertical standard thereon, a pair of spaced arms pivoted to the base at opposite sides of the standard, a shaft journaled in each of the arms, gears fixed to the adjacent ends of the shafts, a circular cutting disk abutting each of said

gears also fixed to the shafts, the cutting disks being arranged tangentially of each other so as to provide a pass therebetween, a spring for constantly but yieldingly urging the arms toward each other causing engagement of the gears, pins slidably mounted in the standard contacting the same to limit their movement under the tension of the spring, means for simultane-

ously and correspondingly adjusting the 10 said pins to vary the width of the pass, a vertically adjustable guide in alignment with the pass, and means for rotating the said shafts.

In testimony whereof, I sign my name.
CHARLES SONNEBORN.

Witness:

EDWIN O. JOHNS.
